UNITED STATES PATENT OFFICE.

CHARLES E. SARGENT, OF INDIANAPOLIS, INDIANA.

SOUND-CONCENTRATING DEVICE.

1,252,039.

Specification of Letters Patent. Patented Jan. 1, 1918.

Application filed March 19, 1917. Serial No. 155,708.

To all whom it may concern:

Be it known that I, CHARLES E. SARGENT, a citizen of the United States, residing at Indianapolis, in the county of Marion and State of Indiana, have invented a new and useful Improvement in Sound-Concentrating Devices, of which the following is a specification.

My invention relates to certain new and useful improvements in sound-concentrating devices and is fully described and explained in the specification and shown in the accompanying drawings, in which:

Figure 1 is a side elevation showing my device in use; Fig. 2 is a top plan, and Fig. 3 is a section on the line 3 of Fig. 2.

Referring to the drawings, 4 is a pair of spectacles of ordinary form having side bows 5 which encircle the ears of the user in the ordinary way. 6 are my sound concentrators. These are made of the lightest possible construction and preferably of one of the cellulose compounds. It is desirable to employ one of the non-inflammable sorts 25 of materials of this kind, and the devices are preferably made transparent or of a light color so that they will be as inconspicuous as possible. Each is of conical form and has a curved end 7 adapted to 30 enter the ear of the user and each is held to the corresponding bow of the spectacles by clips 8.

I thus provide a very light and inconspicuous form of concentrators which may be permanently worn with no particular inconvenience and which will greatly increase the ease of hearing of the wearer.

I realize that considerable variation is possible in the details of this construction without departing from the spirit of my invention; therefore I do not intend to limit myself to the specific form herein shown and described except as pointed out in the following claims, in which it is my intention to claim all the novelty inherent 45 in the construction as broadly as is permitted by the state of the art.

What I claim as new and desire to secure by Letters Patent is:

1. As an article of manufacture the here- 50 indescribed sound concentrator having means whereby to attach it to the side bow of a pair of spectacles.

2. As an article of manufacture the here- 55 indescribed conical sound concentrator of light material and of a suitable length and provided with a curved end to enter the ear and with means whereby to attach it to the side bow of a pair of spectacles.

In testimony whereof I have hereunto set 60 my hand this 14 day of March, 1917.

CHARLES E. SARGENT.
